UNITED STATES PATENT OFFICE.

MONROE GUETT, OF HARTFORD, CONNECTICUT, ASSIGNOR TO THE HART & HEGERMAN MANUFACTURING COMPANY, OF HARTFORD, CONNECTICUT, A CORPORATION OF CONNECTICUT.

ELECTRIC SWITCH.

1,069,126.

Specification of Letters Patent. Patented Aug. 5, 1913.

Application filed June 28, 1911. Serial No. 635,858.

To all whom it may concern:

Be it known that I, MONROE GUETT, a citizen of the United States, and a resident of Hartford, in the county of Hartford and State of Connecticut, have invented certain new and useful Improvements in Electric Switches, of which the following is a specification.

The object of this invention is to produce an electric switch of the push button type having features of novelty and advantage.

In the drawings—Figure 1 is a side elevation of a switch embodying my invention, the receptacle being shown in central vertical section. Fig. 2 is a top view of the switch mechanism. Fig. 3 is a side elevation of the switch mechanism similar to Fig. 1, but with some parts removed to show construction. Fig. 4 is an edge view of the switch mechanism.

Referring to the drawings 1 denotes the spindle on which is loosely mounted a segmental gear 2 having teeth on diametrically opposite sides adapted to engage the racks 3, 4 attached to the push buttons 5, 6, the push buttons and racks being utilized to turn the gear. The longitudinal movement of the racks is guided and limited by the frame plates 7, 7 which are slotted as at 8 and are connected together by rivets 9 which ride in slots 10 in the racks. Fastened to the spindle are a pair of arms 15, 20 on the upper end of which is mounted the circuit-closing contact 25, the arms 15, 20 having spring engaging projections 16, 21 adapted to cooperate with corresponding projections 11, 12 on the gear to hold the ends of the throwing spring 30. In order to hold the arm 15 and the contact 25 against movement during the initial movement of the push buttons, the racks are provided with engaging fingers 35, 36 which are adapted to interlock with the lugs 17, 22 respectively, on the arms 15, 20, these fingers traveling

by and releasing the lugs 17, 22 after the throwing spring has been wound up, with the result that the contact 25 is moved from one position to another with a quick snap action.

This construction is extremely simple and effective and very compact. It is particularly adapted for use in pendant switches but obviously the utility of the invention is not limited to such a structure.

I claim as my invention:

1. In a device of the character described, a spindle, a gear mounted thereon, sliding racks meshing with said gear at opposite points, a push button secured at the end of each rack, an engaging projection at the opposite end of each rack, said push buttons and engaging projections being at opposite sides of the spindle, a contact carrier mounted on the spindle and projecting therefrom on the side opposite the push buttons, engaging projections on the carrier adapted to cooperate one at a time with the engaging projections on the racks, a throwing-spring, and spring-engaging projections on the carrier and gear.

2. In a device of the character described, a spindle, a gear mounted thereon, push buttons at one side of the spindle, racks secured to the push buttons and meshing with said gear at opposite sides, a pair of arms mounted on the spindle projecting to the side thereof opposite the push buttons, a contact mounted on said arms, engaging-lugs projecting from the inner surfaces of said arms, engaging-fingers at the ends of said racks projecting between said arms and adapted to cooperate with said lugs one at a time, a throwing-spring and spring-engaging projections on said carrier and gear.

MONROE GUETT.
